UNITED STATES PATENT OFFICE.

CARLO TONIELLI, OF CHERRY, ILLINOIS.

ELEVATOR SAFETY DEVICE.

1,209,361.

Specification of Letters Patent. Patented Dec. 19, 1916.

Application filed July 31, 1916. Serial No. 112,305.

To all whom it may concern:

Be it known that I, CARLO TONIELLI, a subject of the King of Italy, residing at Cherry, in the county of Bureau and State 5 of Illinois, have invented certain new and useful Improvements in Elevator Safety Devices, of which the following is a specification.

This invention relates to certain new and 10 useful improvements in elevator safety devices.

The primary object of the invention is the provision of an appliance provided in an elevator shaft adapted to coöperate with 15 means upon the car whereby the descent of the car is checked in the event of a severing of the hoisting cable while the stopping of the car at the bottom of the shaft is suitably cushioned.

20 A further object of the device is the provision of a laterally operable cushioning means within an elevator shaft whereby the descending car is cushioned and brought to a stop at such position automatically whenever the occasion arises.

25 The device also contemplates a means for gently causing an elevator car to cease its descent at a pre-determined position in the shaft without being stopped by the operator 30 of the car and also at any time when the hoisting cable of the car is severed.

In the drawings forming a part of this application and in which like designating characters refer to corresponding parts 35 throughout the several views: Figure 1 is a rear elevation of an elevator car partially broken away operatively positioned in the shaft, the car and shaft being provided with the present device. Fig. 2 is a similar view 40 taken from a point adjacent one side of the car. Fig. 3 is a view similar to Fig. 1 with the car in engagement with the cushioning stopping device. Fig. 4 is a top plan view of the car with the shaft beams and hoisting 45 cable shown in horizontal section. Fig. 5 is an enlarged detail horizontal sectional view taken upon line V—V of Fig. 3, and, Fig. 6 is a similar view taken upon line VI—VI of Fig. 5.

50 It being understood that the present device is applicable to any form of elevators, the same is herein illustrated in connection with a box form of car 10 arranged within an elevator shaft 11, a hoisting cable 12 being 55 attached to corner rings 13 carried by a rectangular surrounding top wall 14 upon

the car top 15 whereby the car is vertically operated substantially centrally of the shaft in the usual manner.

The opposite sides 16 of the car are provided with spaced guides 17 freely positioned at opposite sides of vertically arranged beams 18 in the said shaft. Bottom strips 19 are provided in parallel relations upon the bottom of the car arranged upon opposite sides of the beams 18 in a similar manner.

Toothed racks 20 are provided upon the inner faces of the beams 18 arranged outwardly of openings 21 in the adjacent sides 22 of the top wall 14. Locking bars 23 are 70 positioned within the inclosure of the wall 14 in an inclined arrangement with their inner ends attached to a loop 24, the said loop being connected by a cord 25 with the hoisting cable 12 while the outer ends 26 of 75 the said bars are suitably sharpened adapted for engaging the rack teeth 20 in the event of a severing of the cable 12, allowing the bars to fall with the weighted ends 27 positioned upon a central block 28 arranged 80 upon the car top 15 within the wall 14.

The present provision for causing the car to stop in a cushioned manner consists of a plurality of elongated plates 29 hinged at their upper ends as at 30 to the walls of the 85 shaft 11. The said plates and cushioning device may be arranged at any point within the shaft 11 such as at the bottom thereof, as shown in Fig. 2 of the drawings. Adjusting bolts 31 are pivoted at their inner ends 90 within sockets 32 in the adjacent faces of the plates 29 by means of transverse pins 33 carried by the said plates. The outer ends of said bolts freely project through perforations 34 and the adjacent side wall 35 of 95 the shaft being provided with set nuts 36 screw-threaded upon the outer ends adapted for engaging washers 37 arranged in contact with the said wall 35. Helical springs 38 are provided encircling the bolts 31 positioned 100 between the plates 29 and the shaft walls 35 preferably seated at their outer ends within sockets 39 of the said walls.

It will be seen that when the plates 29 are sufficiently released by the nuts 36, the 105 springs 38 will position the plates in inclined arrangement within the shaft. A severing of the cable 12 allows the bars 23 to drop downwardly for engaging the shaft teeth 20 and stopping the downward movement of the car. In the event of a failure of the bar 23 to operate, the car will fall to a 110

position for engaging the plates 29 and will be resiliently engaged by such plates as best illustrated in Fig. 3 of the drawings whereupon the car will be stopped in its downward travel without injury to the car or its contents. In the event that the operator of the car becomes inattentive from sickness or otherwise, the downward movement of the car will be so cushioned and stopped by the plates 29 at the bottom of the shaft although the cable 12 is uninjured. The said plates 29 may also be arranged at intermediate points in the shaft 11 and normally maintained retracted flattened against the walls 35 by means of the nuts 36. At such times the car may freely pass the plates 29. In the event that it becomes desirable to automatically stop the downward movement of the car 16 for any reason, such as the occasion of a fire in the building at a point beneath the position of the plates 29, the nuts 36 may be released, allowing the plates 29 to be projected within the downward path of movement of the car, as the car will then be 40 automatically stopped by the plates 29 when reaching the position at which the said plates are located.

A serviceable device is presented by the invention in the nature of a safety device 30 for protecting both freight and passengers in elevator service and providing for the safety of the car throughout its travel in the elevator shaft.

What I claim as new is:—

35 1. A device of the class described, comprising in combination with an elevator shaft and a car vertically movable therein, depending plates hinged at their upper ends to the walls of the shaft, substantially horizontally arranged bolts pivoted to the inner faces of the said plates and freely projecting

through the said walls, expansion springs surrounding the said bolts between the said plates and walls, and adjusting nuts upon the said bolts outwardly of the said walls. 45

2. A cushioning stopping device for elevator cars comprising downwardly convergent pairs of opposite plates hingedly arranged positioned at desirable points in the elevator shaft, positioning springs in tensioned engagement with the said plates, and adjusting means for the said springs whereby the plates are positioned outwardly of the path of travel of the car within the shaft when desired. 50

3. A cushioning device for elevators comprising in combination with a walled shaft having a car vertically movable therein, upright guide beams for the said car oppositely arranged within the shaft, pairs of depending plates at opposite sides of the said beams, hinge connections between the upper ends of the said plates and the adjacent wall of the shaft, adjusting bolts hinged to the said plates and passed through said shaft 60 walls, springs interposed between the elevator shaft walls and said plates, and retracting adjusting means for the said springs carried by said bolts whereby the plates are flatly positioned against the adjacent wall 65 of the shaft when desired.

4. A safety device for elevators comprising a shaft having side walls, a car vertically movable within the said shaft, depending cushioning plates for the car hinged at 75 their upper ends to the walls at opposite points within the shaft, springs arranged between the said plates and walls, and adjusting means for the said plates.

In testimony whereof I affix my signature. 80

CARLO TONIELLI.
